UNITED STATES PATENT OFFICE

2,001,535

INTERNAL COMBUSTION ENGINE

Franz Lang, Munich, Germany, assignor to
 Lanova Aktiengesellschaft, Vaduz, Liechtenstein

Original application December 1, 1930, Serial No.
 499,224. Divided and this application November
 1, 1933, Serial No. 696,155. In Germany
 December 27, 1929

3 Claims. (Cl. 123—48)

My invention relates to a fuel injection internal combustion engine of the type which embodies an air chamber in which fluid is compressed during the compression stroke of the piston and from which the fluid issues during the working stroke of the piston.

The instant invention is directed to an improved combustion chamber, fuel nozzle and air chamber relationship, and to improved air chamber features, to the end of obtaining thorough mixing of the charge, ease in starting and simplicity of construction, and preventing raw oil from contacting the polished surface of the cylinder. Further objects and advantages of my invention will appear from the detail description.

This application is a division of my copending application, Serial No. 499,224, filed December 1, 1930, for Internal combustion engines.

In the drawings:

Figure 1 is an axial sectional view through the outer end portion of a cylinder of an engine embodying my invention, parts being shown in elevation;

Figure 2 is a section taken substantially on line A—B of Figure 1;

Figure 3 is a view similar to Figure 1, on an enlarged scale, illustrating a modified form of air storage chamber;

Figure 4 is a section taken substantially on line C—D of Figure 3, parts being shown in elevation;

Figure 5 is a central longitudinal section through the modified form of air storage chamber of Figures 3 and 4, on an enlarged scale, parts being shown in elevation and the piston valve being shown in its innermost position; and

Figure 6 is a view similar to Figure 5, but with the piston valve in its outermost position.

The engine illustrated, by way of example, comprises a cylinder *c*, piston *p* operating in the cylinder, cylinder head *h*, and fuel injection nozzle *g* extending through head *h* coaxially with the cylinder.

In the form of my invention illustrated in Figures 1 and 2, plug-like air storage chambers *a*, each comprising an elongated cylindrical casing, screw into bosses *b* integral with head *h* and disposed radially thereof. The chambers *a* open into the combustion space of the cylinder radially thereof, through nozzles *d* each shaped to provide a venturi.

Upon the compression stroke of the piston, fluid from above the piston, mostly pure air, is compressed and stored under high pressure in the chambers *a*. As the piston approaches top dead

center fuel is injected into the combustion space of the cylinder, substantially axially of the latter, by means of nozzle *g*. The upwardly moving piston and the flow of air into the chambers *a* combine to prevent contact of the injected fuel with the polished surface of the cylinder. Injection of fuel continues during predetermined downward travel of the piston, on its working stroke, and during this time the stored air is ejected at high velocity from chambers *a*, through nozzles *d* thereof, into the combustion space of the cylinder. The air streams, entering the cylinder at high velocity and radially thereof, effectively prevent contact of the injected oil with the polished surface of the cylinder. These air streams also impart high turbulence to the charge, assuring thorough intermixing of the air and fuel, which contributes to increased smoothness and efficiency in operation.

In the modified form illustrated in Figures 3 to 6, inclusive, the air chambers are adjustable as to effective capacity. Each air chamber *a'* comprises a preliminary chamber *e* opening, at its outer end, into a main chamber *f*. A piston valve *v* operates in chamber *f* and is provided with conical end elements *i* and *j* which cooperate with corresponding seats *k* and *l* of air chamber *a'* and a sealing plug *m*, respectively, the latter screwing into the outer end of chamber *a'*. Stem *n* of valve *v* screws through plug *m* and is provided, at its outer end, with a hexagonal head *o* for reception of a suitable wrench.

When valve *v* is in its innermost position, as in Figures 3, 4 and 5, the effective capacity of the air storage chamber *a'* is restricted to the preliminary chamber *e*, which is of relatively small volume. This facilitates starting of the engine. After the engine is in operation, valve *v* may be moved into its outermost position, shown in Figure 6, or into any suitable intermediate position. In this connection, valve *v* fits snugly within the main chamber *f* and, if desired, any suitable or preferred packing means may be provided to assure a fluid tight closure between this valve and the surrounding wall of the chamber.

Injection nozzle *g'* may be provided with openings suitably disposed to inject oil into the combustion space of the cylinder radially thereof, as indicated by the arrows in Figure 4, instead of axially of the cylinder as in Figure 1. The air storage chambers *a'* act to store air under high pressure, and this air is ejected into the combustion space of the cylinder radially thereof and at high velocity, acting to prevent contact of raw oil with the polished surface of the cylinder and

to impart high turbulence to the charge, in the same manner as in the engine of Figures 1 and 2.

What I claim is:—

1. In combination in an injection engine, a cylinder and a head therefor, a piston operating in the cylinder and, when in its position of maximum compression, defining with said head and the adjacent end portion of said cylinder a combustion space, an injection nozzle disposed to inject fuel directly into said space, an air storage chamber opening into said combustion space through a restricted orifice and a passage leading thereto from said combustion space, said air storage chamber comprising a preliminary chamber of fixed volume disposed at the outer end of said orifice and a cylindrical main chamber at the outer end of said preliminary chamber and forming a continuation thereof, a cylindrical valve fitting snugly within said main chamber and forming a fluid tight closure with the circumferential wall thereof, and means for adjusting said valve lengthwise of said main chamber.

2. In combination in an injection engine, a cylinder and a head therefor, a piston operating in the cylinder and, when in its position of maximum compression, defining with said head and the adjacent end portion of said cylinder a combustion space, an injection nozzle disposed to inject fuel directly into said space, an air storage chamber opening into said combustion space through a restricted orifice and a passage leading thereto from said combustion space, said air storage chamber comprising a cylindrical preliminary

5
10
inary chamber of fixed volume disposed at the outer end of said orifice and a cylindrical main chamber coaxial with said preliminary chamber and communicating with the outer end thereof through a restricted opening, said main chamber being provided with a valve seat surrounding said opening, a cylindrical valve fitting snugly within said main chamber and forming a fluid tight closure with the circumferential wall thereof, and means for adjusting said valve lengthwise of said main chamber, said valve in its innermost position cooperating with said seat and shutting off communication between said preliminary chamber and said main chamber.

3. In combination in an injection engine, a cylinder and a head therefor, a piston operating in the cylinder and, when in its position of maximum compression, defining with said head and the adjacent end portion of said cylinder a combustion space, an injection nozzle disposed to inject fuel directly into said space, a cylindrical air storage chamber opening into said combustion space through a Venturi nozzle defining a restricted orifice and two passages leading thereto, said passages leading from and flaring toward said combustion space and said air storage chamber, respectively, a cylindrical valve fitting snugly within said air storage chamber and forming a fluid tight closure with the circumferential wall thereof, and means for adjusting said valve lengthwise of said air storage chamber. 15 20 25 30
